US00D612255S

(12) **United States Design Patent**
Shah

(10) **Patent No.:** US D612,255 S
(45) **Date of Patent:** ** Mar. 23, 2010

(54) **CONTAINER**

(75) Inventor: **Sunil S. Shah**, York, PA (US)

(73) Assignee: **Graham Packaging Company, L.P.**,
York, PA (US)

(**) Term: **14 Years**

(21) Appl. No.: **29/331,089**

(22) Filed: **Jan. 20, 2009**

(51) **LOC (9) Cl.** 09-01

(52) **U.S. Cl.** **D9/557**

(58) **Field of Classification Search** D9/502,
D9/516, 538, 541, 549, 556-557, 560, 569-570,
D9/763, 773; 215/381-384; 220/669

See application file for complete search history.

LLC

(57) **CLAIM**

The ornamental design for a “container,” as shown and described.

DESCRIPTION

FIG. 1 is a perspective view showing my new design;

FIG. 2 is a front elevational view thereof, the rear elevational view being identical;

FIG. 3 is a left side elevational view thereof, the right side elevational view being identical;

FIG. 4 is a top plan view thereof; and,

FIG. 5 is a bottom plan view thereof.

The broken lines shown in the drawing views are included for the purpose of showing environmental structure that forms no part of the claimed design.
